UNITED STATES PATENT OFFICE.

JAMES W. DE CAMP, OF BLACKWELL, OKLAHOMA.

GLASS CASKET AND CARRIER THEREFOR.

1,349,412.

Specification of Letters Patent. Patented Aug. 10, 1920.

Application filed June 17, 1918. Serial No. 240,453.

To all whom it may concern:

Be it known that I, JAMES W. DE CAMP, a citizen of the United States, residing at Blackwell, in the county of Kay and State 5 of Oklahoma, have invented certain new and useful Improvements in Glass Caskets and Carriers Therefor, of which the following is a specification.

This invention relates to improvements in 10 glass caskets and carriers therefor, and so far as the casket itself is concerned, is designed as an improvement over the casket shown and described in my Patent No. 1,211,684, issued January 9, 1917. In the 15 patented structure the glass body and lid of the casket are bound or confined within a frame comprising an arrangement of metallic straps which are buried with the casket. Also in the patented structure the 20 frame for the body includes a metallic strap extending exteriorly around the top of the body, and the frame for the lid includes a strap extending around the bottom of the said lid, these straps being connected at one 25 side of the casket by suitable hinges, and certain of the straps of the respective frames being secured to the said encircling or surrounding straps to be held in place thereby and also for the purpose of holding the 30 said encircling or surrounding straps against displacement in the opening and closing of the lid upon its hinges. Therefore, so far as the casket itself is concerned, the present invention has as its object to 35 provide a less expensive construction by dispensing with all of the frame straps with the exception of the said encircling or surrounding straps for the body and lid, novel means being provided by the present invention 40 for securing these straps to the respective casket members.

A further object of the invention is to provide a carrier within which the casket may be bodily placed, the carrier being, 45 however, only temporarily connected with the casket so that prior to interment the said carrier may be separated from the casket and thus save a considerable quantity of metal which would otherwise be a total 50 loss.

Another object of the invention is to provide a casket carrier which may be highly ornamental in its embellishments and in itself more or less expensive, and which, after it has served its purpose and before inter-

ment, may be readily separated from the casket and reserved for future use.

Another object of the invention is to provide means whereby the carrier may be temporarily secured upon the casket body 60 and which means will be inconspicuous.

A further object of the invention is the provision of novel means for securing a wooden base against the under side of the bottom of the casket so as to provide against 65 breakage.

In the accompanying drawings:

Figure 1 is a perspective view illustrating one embodiment of the present invention;

Fig. 2 is a perspective view illustrating the carrier removed from the casket;

Fig. 3 is a perspective view of the protective base member for the casket and the means provided for securing the same in 75 place;

Fig. 4 is a vertical transverse sectional view through the casket and the carrier;

Fig. 5 is a perspective view of one end of the casket with the carrier removed and 80 also the protective base member and the encircling bands or straps which constitute a part of the hinge construction between the lid and body of the casket;

Fig. 6 is a fragmentary perspective view 85 illustrating a portion of the securing means for the protective base member;

Fig. 7 is a vertical transverse sectional view taken substantially on the line 7—7 of Fig. 1.

The body of the casket is indicated in general by the numeral 1 and the lid by the numeral 2, and the said body includes sides 3, ends 4, diagonal corner portions 5, and a bottom 6. In like manner the lid of the 95 casket includes sides 7, ends 8, diagonal corner portions 9, and a top 10. Externally the walls 3, 4 and 5 of the body of the casket are formed at their upper edges with a continuously extending shallow rabbet or 100 groove 11, and a similar rabbet or groove 12 is formed externally in the walls 7, 8 and 9 of the lid at the lower edges thereof, each rabbet or groove defining a circumferential stop shoulder or ledge, as shown. Seated 105 within the rabbets or grooves 11 and 12 respectively, are bands or straps 13 and 14 the said bands or straps extending respectively continuously around the body and the lid of the casket. In order to secure the 110

said straps in place, the corner portions 5 and 9 of the body and lid are formed each with a socket 15 into which is fitted a plug or bushing 16 preferably of hard rubber 5 although any other suitable material may be employed for the purpose. Each bushing 16 is formed with a socket 17 which opens through the outer end of the bushing and may either terminate short of the inner end 10 thereof or open through said end. The outer ends of the bushings 16 terminate at the vertical walls of the rabbets 11 or 12 as the case may be, and are, consequently, held against displacement from the sockets 15 by 15 the encircling bands or straps. At the points of location of the bushings 16, the said bands or straps are formed with openings 18 which are preferably threaded, and securing screws or bolts 19 are fitted into these openings and 20 at their inner ends extend into the sockets 17, as clearly shown in Fig. 7 of the drawings. As the bushings are held against displacement in the manner above stated, it will be readily understood that the straps 25 or bands 13 and 14 are securely held against displacement from their respective receiving rabbets. At one side of the casket, hinges 20 have their leaves secured to the said bands 13 and 14 and in this manner the lid of the 30 casket is connected with the body for swinging movement to open and closed positions. From the foregoing it will be understood that due to the provision of the means above described for securing the straps or bands 35 13 and 14 in place, the use of transversely extending straps or bands as in the patented structure is obviated. Of course, the structure illustrated and described in the patent 40 is preferable as it is much more substantial and, therefore, the improvements so far described are applicable chiefly to caskets which are intended to be sold at a relatively low price or where, for other reasons, it is desirable or necessary to economize in the 45 use of metal. It will, furthermore, be evident from an inspection of the drawings and a consideration of the description which is to follow relative to the carrier, that any other type of carrier or any suitable casket 50 harness may be employed. However, regardless of the employment of any particular type of carrier or harness, it is desirable that the bottom of the casket body be protected in the manner which will now be explained.

The protective means above referred to comprises a base 21 which is preferably of wood and of such dimensions as to cover the entire under surface of the bottom 6 of the 55 body. In order to secure the base 21 in position there is provided a frame indicated in general by the numeral 22 and comprising an upstanding portion or flange 23 and a horizontally disposed flange 24. The flange 60 23 is designed to surround the lower portion

of the body of the casket and the margin of the protective base 21, while the flange 24 extends beneath the edge portion of the protective base, as clearly shown in Fig. 4 of the drawings. In order to suitably anchor 70 the flange 24 to the protective base, it is preferable that the flange be provided at its edge, at suitable intervals, with upstanding spurs 25 which may enter the under side of the said protective base. In securing the 75 flange 23 to the casket body, securing means identical with the securing means shown in Fig. 7 of the drawings and heretofore described and indicated in the said drawings by corresponding numerals, is employed, 80 the securing screws or bolts 19 of said means passing through openings 26 formed at the proper points in the said flange 23. As the flange 23 is only of such height as to permit of the employment of the securing means 85 above mentioned, and the flange 24 is relatively narrow, it will be understood that the frame comprising these flanges will not only be inconspicuous but will, at the same time, require but little metal for its manufacture, 90 and yet it serves as a highly efficient means for securing the said protective base 21 in place.

The carrying device embodying the present invention is in the nature of a basket-like structure within which the body of the casket is to be disposed and which is to be temporarily secured to the said casket. The carrier is preferably formed in two sections indicated by the numeral 27, each section being designed to fit one diagonal half of the casket body. The said sections at one end are preferably connected by hinges 28 so that the sections may be swung together in applying the carrier to the casket body or swung apart 105 in removing the same from the casket. At its opposite end, one of these sections is preferably provided with one or more ears 29 designed to overlap the corresponding end of the other section, and suitable securing 110 screws or other elements 30 are fitted through the ears and into the said corresponding end of the other section in order to hold the sections closed about the body of the casket. Of course, if desired, suitable snap fastenings might be provided for the purpose of connecting the last-mentioned ends of the sections and, in fact, if desired, the hinges 115 might be replaced by some means for separately connecting the first-mentioned ends 28 120 of the said sections. The sections 27 are formed at their lower edges with inwardly projecting flanges 31 which are designed to extend beneath the flanges 24 of the protective base securing member 22, as clearly 125 shown in Fig. 4 of the drawings. The sections of the carrier are, as stated above, formed of sheet metal, and these sections may be plain or highly ornamented as desired and as illustrated in Figs. 1 and 2 of the 130

drawings, the upper edges of the sections may be scalloped, undulated, or otherwise fashioned so as to impart an ornamental appearance to the carrier as a whole.

- 5 That wall of each section which extends beside the corresponding side wall of the casket body is provided with means for temporary connection with the circumscribing band 13 so that after the sections have been 10 swung together to encompass the casket body, the said sections may be connected with the casket to prevent accidental displacement while the casket is being carried and up to the time it is desired to permanently 15 separate the carrier from the casket. While various devices may be provided for affording connection between the sections of the carrier and the said band 13, it is preferable that means such as illustrated in the drawings be made use of. Any number of the connecting devices may be employed between each section of the carrier and the binding strap 13. Each of the devices comprises a lever member indicated in general 20 by the numeral 32 and pivotally or hingedly connected as at 33 with the upper edge of the respective carrier section, the lever member being adapted to be swung in a vertical direction. The numeral 34 indicates a hook 25 member provided at its lower end with a fork, the arms 35 of which are pivotally connected to an intermediate portion of the lever member 32 and are spread sufficiently to straddle the pivotal or hinge connection 33 30 when the lever 32 is swung downwardly to lie against the outer face of the respective carrier section. The hook member 34 at its upper end is provided with a bill 36 and the said bill is designed to engage in a socket 37 35 formed by striking out the upper portion of the strap or band 13 at points corresponding to the points of location of the connecting devices when the carrier is in position encompassing the body of the casket. It will 40 now be understood and particularly by reference to Figs. 1, 2 and 4 of the drawings, that when the lever members 32 are swung upwardly, the terminals of the bills 36 of the hook members 34 may be engaged over the 45 upper edges of the band 13 at the points of location of the sockets 37, and when the lever members 32 are swung downwardly, the hook members 34 will be drawn in a corresponding direction causing the bills 36 to 50 enter the sockets 37, and after the arms 35 of the forks of the hook members have passed the pivotal or hinge connections 33, the pivots for the hook members 34 will have passed dead center and consequently 55 the devices will be held against disarrangement until the lever members 32 are manually and positively swung outwardly to release the connecting devices from the band 13. In practice a strip of felt (not shown) 60 65 will be applied between the strap or band 13

and the wall of the groove or rabbet 11 at the upper edge of the walls of the body of the casket as in my prior patent heretofore mentioned, and it will be understood that by providing the sockets 37 in the said band or 70 strap 13, the bills of the hook members 34 may seat in the sockets without pushing down or otherwise distorting or tearing the felt strip.

Having thus described the invention, what 75 is claimed as new is:

1. In a casket, a glass body and a glass lid each provided at their abutting edges with a circumscribing seating groove defining a continuous stop shoulder, bands 80 seated in said grooves and bearing against the stop shoulders, said body and lid being provided with transverse sockets formed in the exterior walls of the casket at said seating grooves, bushings fitting within the 85 sockets and having their outer faces disposed substantially flush with the walls of the seating grooves, and securing means carried by the bands and projecting into said bushings, said bands bearing against 90 and forming closures for the bushings.

2. In a glass casket, a body provided near its upper edge with a circumscribing seating groove defining a continuous stop shoulder, a band fitted in said seating groove and 95 bearing against the stop shoulder, the body being formed with a transverse socket across which the band extends, a bushing fitted in the socket with its outer end disposed substantially flush with the wall of the 100 groove and retained within the socket by engagement with said band, and an anchoring element extending through said band and fitting into the bushing, said band bearing against and forming a closure for 105 the bushing.

3. In a glass casket, a protective base member disposed against the under side of the bottom of the casket, means for holding said protective base member in place comprising an open frame having an upstanding flange and an inwardly extending flange, the last-mentioned flange projecting beneath the marginal portion of the base member, the first-mentioned flange extending 110 across the edge of said base member and upwardly in contact with the exterior walls 115 of the casket, and means for preventing displacement of said frame.

4. The combination with a glass casket, 120 of a protective base member therefor disposed against the under side of the bottom of the casket, an open frame extending around the lower portion of the casket and the marginal edge of the base member, and 125 a basket-like structure fitted to the lower portion of the casket and provided with an inwardly extending flange bearing against said frame.

5. The combination with a glass casket, 130

- of a protective base member therefor disposed against the under side of the bottom of the casket, an open frame extending around the lower portion of the casket at 5 its junction with the base member and including a horizontal supporting flange extending beneath the marginal portion of said base member, and a basket-like structure fitted to the lower portion of the casket 10 and provided with an inwardly extending flange bearing against the horizontal flange of said frame.
6. The combination with a glass casket, of a protective base member disposed against 15 the under side of the bottom of the casket, an open frame extending around said bottom of the casket and bearing against the exterior walls thereof and against the marginal edge of the protective base, said frame 20 being provided with an inwardly extending flange projecting beneath and bearing against the protective base member, said flange being provided with upstanding spurs the points of which are embedded in said 25 base member.
7. The combination with a casket, of a carrier therefor comprising mating sections having a hinge connection and conforming substantially to the contour of the casket 30 and each provided with an inwardly extending rigid flange projecting partially beneath the bottom of the casket, and means removably securing the sections of said carrier about the casket.
8. The combination with a glass casket having a band extending around the upper portion thereof, of a carrier for the casket comprising vertical walls hingedly connected for lateral swinging movement and 35 fitted to the lower portion of the casket, means for securing the walls of the carrier about the casket and means detachably securing the carrier to said band.
- 40
9. The combination with a casket, of a carrier comprising mating sections formed of vertical walls having corner portions hingedly connected with each other to permit lateral swinging movement of said sections with respect to the casket, and means removably securing the sections of the carrier about said casket. 50
10. The combination with a casket, of a carrier comprising sections conforming to the contour of the casket and bearing against the exterior walls of said casket for 55 substantially the major portion of the height thereof, said sections being hingedly connected with each other at one point and at the opposite point being provided with means whereby they may be held closed about the casket body, the lower edges of the sections being provided with inwardly projecting flanges adapted to extend beneath the bottom of the casket. 60
11. The combination with a glass casket, 65 of a carrier therefor comprising a basket-like structure fitted to the lower portion of the casket, a band extending around the upper portion of the casket, and connecting means carried by the said structure and 70 having elements detachably engageable over the upper edge of the said band.
12. The combination with a glass casket, 75 of a carrier therefor comprising a basket-like structure fitted to the lower portion of the casket, a band extending around the upper portion of the casket, and connecting means carried by the said structure and having elements detachably engageable over the upper edge of the said band, the band 80 at intervals being struck out to provide sockets to receive the said elements.

In testimony whereof I affix my signature.

JAMES W. DE CAMP. [L. S.]
